PORTABLE DITCH PUMP

Lloyd K. Schmidt, Walnut Grove, Calif., assignor
of one-half to Albert M. Jongeneel, Walnut
Grove, Calif.

Continuation of abandoned application Serial No.
736,915, March 25, 1947. This application Feb-
ruary 16, 1953, Serial No. 336,940

4 Claims. (Cl. 103—202)

1

This application is a continuation of application Serial No. 736,915, filed March 25, 1947, now abandoned.

This invention is directed to, and it is an object to provide, a novel, portable pump adapted to lift water from an irrigation ditch and discharge such water into an adjacent field.

Another object of the invention is to provide a portable ditch pump, for the purpose described, which includes an intake pipe and a discharge pipe, both of substantial length; the intake pipe projecting rearwardly and being mounted for vertical adjustment between an elevated position for transport and a lowered position for pumping.

A further object of the invention is to provide a portable ditch pump, as in the preceding paragraph, in which the discharge pipe normally projects laterally, but is mounted, by unique means, for adjustment to a rearwardly projecting position for transport.

An additional object of the invention is to provide a portable ditch pump which comprises, in combination with a wheel-supported vehicle frame, an intermediate pipe extending transversely of the frame and mounted for rotation about a transverse axis; the intake pipe extending from one end of the intermediate pipe and the discharge pipe extending from the other end of said intermediate pipe; there being a novel winch, mast, and lift cable system assembly operative to selectively raise or lower said intake pipe with the rotatable intermediate pipe as its axis.

It is also an object of the invention to provide a novel hinge and gasket arrangement between adjacent ends of the discharge pipe and the intermediate pipe.

A further object of the invention is to provide a practical and readily portable device, and yet one which will be exceedingly effective for the purpose for which it is designed.

These objects are accomplished by means of such structure and relative arrangement of parts, as will fully appear by a perusal of the following specification and claims.

In the drawings:

Fig. 1 is a side elevation of the portable ditch pump.

Fig. 2 is a plan view of the same.

Fig. 3 is an enlarged fragmentary elevation of the hinge and gasket arrangement between adjacent ends of the discharge pipe and intermediate pipe.

Referring now more particularly to the characters of reference on the drawings, the portable

2

ditch pump comprises a vehicle frame 1 adapted for movement along the ground, which frame may be part of any type of vehicle, such as a truck or trailer; a trailer being shown in the present embodiment. The frame 1 is supported, adjacent its rear end, by wheels 2. At its forward end the frame 1 includes a hitch 3 adapted for connection.

At its rear end the frame 1 is fitted, in rigid relation, with a pair of rearwardly projecting, relatively large-diameter collars 4 disposed in transversely spaced, axial alignment; said collars being of split type to permit of proper diametral adjustment thereof.

15 The collars 4 engage about a transversely extending, horizontal pipe 5, hereinafter referred to as the intermediate pipe, and support such pipe in relatively rotatable relation.

At one end, which is disposed a considerable 20 distance laterally of the frame 1, the intermediate pipe 5 connects in communication with an intake pipe 6 disposed at right angles and projecting rearwardly. Said intake pipe 6 is vertically adjustably suspended by a lift cable system 7, 25 which extends from the outer end portion of said pipe 6, as at 8, upwardly and rearwardly, on the diagonal, to the upper end of a rigid mast 9 which upstands from the frame 1 at its rear end. From the upper end of the mast 9 the lift cable system 7 includes a pull lead 10 which extends downwardly to a hand winch 11 on the frame 1. It will be seen that by manipulation of the winch 11, the intake pipe 6 may be adjusted between a rearwardly and downwardly inclined 30 position for pumping, and a rearwardly and upwardly inclined position for transport. With such adjustment of the intake pipe 6 the intermediate pipe 5 rotates in the collars 4 and thus provides 35 the axis of rotation.

The intake pipe 6 carries a pump assembly comprising a pump shaft 12 extending axially in the intake pipe 6, being supported by bearings where necessary. At the lower end of said intake pipe the pump shaft 12 is fitted with an impeller 14, 45 and a screen 13 prevents entry of foreign matter, such as weeds, etc., into the intake pipe with possible damage to the impeller 14.

At the end opposite the impeller 14 the pump shaft 12 is exposed, and carries a multi-groove pulley 15 driven by a plurality of flexible V-belts 16 from another multi-groove pulley 17 on the rear end of a drive shaft 18 journaled longitudinally on the frame 1 by means including a bearing 19.

As the belts 16 are of substantial length they

3

absorb the twist imparted thereto upon vertical adjustment of the intake pipe 6, and this adjustment thus does not harm the driving arrangement.

The drive shaft 18 is coupled, at its forward end, in connection with a hood 21; there being a clutch 22 interposed in said drive shaft.

A relatively long discharge pipe 23 normally projects laterally outwardly from the end of the intermediate pipe 5 opposite the intake pipe 6. Adjacent ends of the intermediate pipe 5 and discharge pipe 23 are formed with cooperating radial flanges 24, with a compressible gasket 25 interposed therebetween to prevent leakage when the pump is in operation.

The discharge pipe 23 is connected to the intermediate pipe 5 on the rear sides of the same, by a hinge, indicated generally at 26, having a generally upstanding axis, whereby said discharge pipe 23 may swing from its operative, laterally outwardly projecting position, shown in full lines in Fig. 2, to a rearwardly projecting position parallel to the intake pipe 6, for transport, as shown in dotted lines in said figure.

In this transport position the discharge pipe 23 extends at a slight upward and rearward incline to facilitate transport, which incline is occasioned by corresponding inclination of the hinge pin 27 of the hinge 26. The discharge pipe 23 is maintained in its folded or transport position by means of a detachable tie rod 28 which connects between ears 29 on adjacent sides of said pipes 6 and 23, intermediate their ends.

When the discharge pipe 23 is in its laterally outwardly projecting, working position, the radial flanges 24 tightly compress the gasket 25 therebetween in non-leaking relation by means of the following arrangement:

On its front side, and adjacent the corresponding flange 24, the discharge pipe 23 includes a 40 forwardly projecting slotted ear 30, and a horizontal, swingably mounted tension bolt 31 projects from the adjacent part of the frame 1 and engages in said slotted ear 30.

On the opposite side of the discharge pipe 23 there is the hinge 26, which includes one pair of ears 32 fixed to the pipe 23, while the other pair of ears 33 are fixed to a slide plate 34. The pairs of ears 32 and 33 are coupled together by the hinge pin 27.

The slide plate 34 is slidably mounted on the back side of the intermediate pipe 5, and for horizontal motion transversely of the implement, as follows:

The slide plate 34 rests against a backing plate 35 fixed in connection with, and extending between, the collars 4; such backing plate including upper and lower guide flanges 36 between which the slide plate 34 engages. The slide plate 34 is formed with longitudinally elongated slots 37, and bolts 38 extend through said slots into the backing plate 35. A link 39 pivotally connects between the outer end of the slide plate 34 and the fork 40 of an off-center lever 41. In the position of the lever shown in Fig. 3, the link 39 is tensioned, urging the slide plate 34 in a corresponding direction, which shifts the hinge 26 in a direction to compress the gasket 25; the tension bolt 31 having been pre-set to proper tension.

Upon release of the lever 41 the link 39 and slide plate 34 shift toward the discharge pipe 23, whereupon the hinge 26 relieves the tension on the gasket 25. When this occurs the tension bolt 31 can be swung out of the slotted ear 30 and

4

the discharge pipe 23 turned rearwardly to its transport position.

A swivelly connected stay 42 connects between the discharge pipe 23 intermediate its ends and the top of the mast 9, whereby to stabilize said pipe as it is swung between its respective positions of adjustment.

When the above described portable ditch pump is in operation, the vehicle part is disposed on the bank 43 alongside the ditch 44 from which water is to be pumped, and the intake pipe 6 is lowered into such ditch in the manner shown in Fig. 1. The discharge pipe 23 is then adjusted from its transport position to its working position, projecting laterally outwardly, whence it discharges into the field alongside the bank 43 on the side opposite the ditch 44.

With the parts positioned as above, the engine is started, whence a drive is imparted to the impeller 13, which pumps water from the ditch, through the described pipe assembly, into the field.

By reason of its practical and convenient arrangement, the pump can be moved along a ditch bank point by point to thoroughly, and yet easily, irrigate a field of relatively large size; the adjustment of the intake and discharge pipe sections between their working and transport positions being a matter of simple manipulation, which the operator can accomplish in a few moments.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

- 45 1. A water pumping means comprising the combination of: a vehicle adapted for transport from point to point; a pipe mounted on the vehicle adjacent the rear end thereof above ground level and disposed transversely of the vehicle, the pipe being rotatable in its mounting about its longitudinal axis; a fixed extension on one end of the pipe extending at substantially right angles thereto and adapted to be lowered into or lifted out of a water sump upon turning of the pipe; a pump disposed in the extension; power means on the vehicle operatively connected with the pump; an extension on the other end of the pipe; such last named extension being adapted to be extended in end to end relation with the pipe when the first extension is in a sump, and such last named extension being hinged to the pipe for swinging movement in a direction rearwardly of the vehicle; and releasable means for clamping the last named extension in such end to end relation with the pipe.

- 50 2. A combination, as in claim 1, in which such releasable means includes a tension bolt secured in fixed position adjacent but separate from the inner end of the last named extension, and means for releasably connecting the tension bolt with the inner end of the last named extension at a point opposite the hinge.

- 55 3. A combination, as in claim 1, in which such releasable means includes a tension bolt secured in fixed position adjacent but separate from the

inner end of said last named extension, means for releasably connecting the tension bolt with the inner end of said last named extension at a point opposite the hinge, a slide element connected between the pipe and the last named extension and mounted for movement lengthwise of the pipe, and a releasable off-center lever assembly connected to said slide in actuating relation thereto; said lever unit, when in a predetermined off-center and locking position function-

ing to urge the slide in a direction to draw the inner end of the last named extension against the adjacent end of the pipe.

4. A combination, as in claim 3, including a compressible gasket interposed between the pipe and the inner end of said last named extension.
